COIN CASE

Richards L. Loesch, Montrose, Colo.

Application March 18, 1941, Serial No. 383,990

11 Claims. (Cl. 133—6)

My invention relates generally to coin cases, and more particularly to a coin case for carrying a plurality of coins of each of a plurality of denominations separately, and adapted to be carried in a handbag or a pocket in the user's clothing.

This application is a continuation in part of my prior application, Serial No. 266,270, filed April 6, 1939.

It is an object of my invention to provide a novel pocket size coin case which is compact and light in weight and from which a plurality of coins of each of several denominations may be readily dispensed.

Another object of my invention is to provide a novel coin case which may easily be operated by one hand, and which the user may conveniently operate in the dark by the sense of touch alone, to dispense the desired number of coins of the desired denomination.

Another object is to provide a coin case having a plurality of coin retaining cylinders, one for each of several denominations of coins, which may be easily operated with one hand to insert a coin in the cylinder corresponding to the denomination of the coin.

A further object is to provide a light, simple coin case which may be cheaply manufactured in large quantities.

A further object is to provide a novel coin case of a durable construction and which may be easily cleaned by the user.

Further objects will appear from the following description, reference being had to the accompanying drawings in which:

Fig. 1 is a top plan view of my improved coin case, showing coins in position in the various coin retaining cylinders;

Fig. 2 is a view similar to Fig. 1 and shows my improved coin case with the coins removed;

Fig. 3 is a vertical cross-sectional view of my improved coin case along the plane of the line 3—3 of Fig. 1;

Fig. 4 is a horizontal cross-sectional view taken along the plane of the line 4—4 of Fig. 3;

Fig. 5 is a side elevational view taken in the direction indicated by the line 5—5 in Fig. 1;

Fig. 6 is a vertical cross-sectional view taken along the plane of the line 6—6 of Fig. 1; and

Fig. 7 is a perspective drawing of the upper member of the spring which forces the coins upwardly from the lower portion of the cylinder.

In Fig. 1, I have illustrated a coin case comprising a relatively thin, generally cylindrical body 10, which is preferably of thermo-setting

plastic or similar material. This body 10 has cast therein a plurality of cylindrical openings which are circumferentially disposed and spaced inwardly from the periphery of the body and which are hereinafter referred to as "coin retaining cylinders." These coin retaining cylinders are designated by the reference characters 22, 24, 26, and 28. The penny 12, dime 14, nickel 16, and quarter 18, are shown as being located in the coin retaining cylinders, which are adapted to hold these respective denominations. The cylinders for containing the dimes and quarters are placed opposite each other to reduce the overall diameter of the coin case.

The top center portion of the case is recessed to retain coins being placed therein, leaving a rim 11 which extends around the periphery of the top of the body 10. The recess so formed intersects and interrupts the walls of the coin retaining cylinders to provide for and facilitate the introduction of coins into the cylinders. Buttons 20 are integrally formed on the upper surface of the rim, one button 20 being located opposite the dime cylinder 24, two buttons 20 opposite the penny cylinder 22, and three buttons 20 opposite the nickel cylinder 26. These buttons 20 serve to aid the operator of the case to ascertain the denomination in each of the cylinders by the sense of touch. The number of buttons corresponding to each denomination may be easily associated in the user's mind inasmuch as the number of buttons increases as the diameter of the corresponding coin increases, with the exception of the quarter cylinder 28 which has no corresponding indicating button 20.

A plurality of crescent shaped continuous abutments 30, one for each cylinder, are integrally formed with the rim 11. Each abutment overhangs the top of the half of the corresponding cylinder which is adjacent the periphery of the case. The abutments 30, being of crescent shape, do not cover the central portion of the coin retaining cylinder, but permit free access to the upper surface of the top coin in the cylinder. The top of the overhanging portion of each abutment 30 is beveled or rounded to facilitate the insertion of coins into the coin retaining cylinders. The abutments 30 are shaped and disposed to allow the coin to be moved from the center of the case, across the upper end of the proper coin retaining cylinder, through a coin removal slot 58, to the outside of the case, as is herein-after described.

As is shown in Figs. 2 and 3, a flat spring 34 is constructed to provide a plurality of spring

arms 32, and one of these spring arms 32 extends into each of the coin retaining cylinders. Each spring arm 32 tapers outwardly from the center of the body 10. The various arms intersect adjacent the lower ends of the coin retaining cylinders when the spring is in position. Each arm 32 tapers outwardly from the central portion of the spring 34, and the arm is of sufficient length and the outer end thereof is of sufficient width to engage the under surface of the corresponding abutment 38 on both sides of the coin retaining cylinder when the cylinder is empty. The outer end of each of the spring arms 32 is shaped and disposed to coincide with a chord connecting two points on the undersurface of the corresponding crescent shaped abutment 38 when the case is assembled and the cylinder is empty. The undersurface of each crescent shaped abutment 38 is perpendicular to the axis of the corresponding cylinder so that the spring arm 32 positively holds the coins in a position level with the top of the cylinder by pressing the top coin against the undersurface of the corresponding abutment 38.

The use of a flat spring in the manner described allows the coin retaining cylinders to receive more coins than if a spring of a different form were used, inasmuch as when the cylinders are full, the flat spring is pressed closely against and parallel to the bottom 36 of the case and in this position it occupies very little space.

The flat spring 34, as is shown in Fig. 7, has a small hole 38 disposed toward one corner of the center portion thereof. The location of this hole 38 is such that the hole will coincide with the axis of the body 10 when the case is assembled. As is shown in Fig. 4, a smaller reinforcing spring 40, which is placed underneath the spring 34 when the case is assembled, is added to increase the stiffness of the spring 34 and thereby increase the pressure exerted upon each of the coins in the cylinder. This reinforcing spring 40 has a small hole 42 therein which registers with the hole 38 of the spring 34 when the case is assembled. As is shown in Fig. 6, the bottom of the body 10 has a recess 44 therein to accommodate the springs 34 and 40. This recess intersects and interrupts a portion of the walls of each of the coin retaining cylinders so that each of the flat spring arms 32 may extend into a corresponding cylinder.

The circular bottom plate 36, which also is preferably of thermo-setting plastic, has a small metal peg 46 formed therein at the exact center thereof. The peripheral portion of the body 10 is extended downwardly and the extension has internal threads 48 formed therein to engage corresponding threads formed in the periphery of the bottom plate 36. In assembling the coin case, the springs 34, 40 are placed in position, the metal peg 46 is inserted through the registering holes 38 and 42 of the springs 34 and 40, and the bottom plate 36 is then screwed into the body portion 10.

Coin removal slots 58 extend through the body 10 and intersect the corresponding cylinder adjacent its top to provide for the removal of coins from the case. The upper portion of each of these slots 58 is non-planar with the underportion of the corresponding coin retaining lip 38, and the slot is preferably longer and wider than the greatest vertical cross section of the corresponding coin so that the coins may be freely moved through the slot.

To decrease the overall size of the case, the

coin retaining cylinders are placed as closely together as possible. The segments which separate the coin retaining cylinders each from the other are in the form of webs 50, made integral with the body 10 and of a thinness to permit as close juxtaposition of the cylinders as is consistent with the strength of the finished case. An upwardly extending projection 52 is formed at approximately the thinnest point of each web and extends upward from the web 50 a sufficient distance to bear against the edge of the second coin from the top in each of the cylinders, as is shown in Fig. 6. The projections on each side of each coin retaining cylinder cooperate, each with the other, to engage the periphery of the second coin from the top in each cylinder, thereby preventing that coin from moving inwardly toward the center of the case. The center portion 54 of the body 10 is made integral with the webs 50. As is shown in Fig. 3, the top of the center portion 54 is concave and is recessed below the under edge of the top coin in the coin retaining cylinders to facilitate the insertion and removal of coins as is hereinafter described.

In operation, the coin case may be held by the palm and fingers of one hand and a coin may be placed in the depression formed in the top of the case. The coin may then be shifted by the thumb into the proper coin retaining cylinder and slid under the corresponding crescent shaped abutment 38. In the construction above described, the center portion 54 of the case is recessed as much as possible to allow full action of the thumb and to facilitate the placing of coins in their proper cylinders. Inasmuch as the coin retaining abutments 38 are crescent shaped so that they cover only that portion of the upper surface of the coin adjacent the periphery of the outer half thereof, the thumb may be placed on the upper surface of the coin directly over the end of the spring arm 32 and the coin may be pressed directly downwardly against the force exerted by the spring as it is moved into position.

The positioning of the thumb directly above the end of the spring arm 32 controls any tendency of the coin to tilt when it is being placed in the cylinder. If the thumb could not be placed directly over the end of the spring arm 32 it would be more difficult to properly locate the coin within the cylinder, inasmuch as the coin would then act as a lever in depressing the spring, and the edge of the coin on the side of the cylinder opposite the coin engaging end of the spring arm would have to be depressed very nearly to the bottom of the cylinder before it would strike a firm bearing surface so that it could act as a fulcrum.

The downward pressure of the thumb on the top surface of the coin compresses the spring sufficiently to depress the coin below the lower edge of the slot 58 so that the coin engages the walls of the cylinder and is prevented from being moved into the slot. The downward pressure also causes the edge of the coin to be depressed below the top of the coin retaining projections 52, thereby preventing the coin from being accidentally moved from the cylinder toward the center of the case.

A feature of my invention lies in the provision of the flat spring 32, which permits the forward or outer edges of the coins to be tilted as they are being introduced into the cylinders, and which at the same time prevents the coins from tilting sideways.

A second coin may then be slid over the top of the first coin and pressed downwardly under the

lip 30, and it will similarly be depressed sufficiently to engage the coin retaining surfaces bordering the cylinder. In a like manner, each of the cylinders may be filled with coins. The top coin in each cylinder is retained in position by the friction caused by the pressure exerted by the arms 32 of the flat spring assembly.

If it is desired to remove a coin from the case, the thumb is passed over the top of the rim 11 so that it engages the knobs 20 and the proper cylinder may be ascertained by the sense of touch. The thumb is then placed on the depressed center portion 54 of the case 10 with its tip opposite the cylinder containing coins of the denomination desired. The tip of the thumb is then moved outwardly across the case, engaging the edge of the top coin and pushing the coin through the corresponding coin removal slot 58. As the thumb passes over the top surface of the second coin in the cylinder a downward pressure may be exerted upon the second coin to prevent the spring arm 32 from exerting a pressure which would cause the top coin to be frictionally retained against the under surface of the abutment 30 and the coin will pass freely through the slot 58. When the coin has been removed and the thumb pressure released, the spring arm 32 will cause the remaining coins in the cylinder to move upwardly so that the top coin remaining in the cylinder engages the undersurface of the abutment 30, from which position it also may similarly be removed from the case.

While I have described my invention in connection with a preferred embodiment thereof, it will be apparent to those skilled in the art that numerous variations and modifications may be made from the structure disclosed without departing from the underlying principles of my invention. I, therefore, wish to include within the scope of the following claims all constructions by which substantially the results of my invention may be obtained by substantially the same or equivalent means.

I claim:

1. A pocket size coin case for carrying a plurality of coins of each of a number of denominations and comprising a body of generally cylindrical outline, a plurality of coin retaining cylinders, one for each denomination, circumferentially disposed within said body and spaced inwardly from the periphery thereof, a plurality of overhanging abutments carried by said body, one of said abutments overhanging the outer half of the top of each of said cylinders and projecting a relatively short distance inwardly past the walls of the cylinder, a plurality of slots, one adjacent the top of each cylinder, connecting the top of the corresponding cylinder with the outside of said body to permit the movement of a coin from said cylinder through said slot to the outside of said body, resilient means for causing the uppermost of said coins to engage the undersurface of the corresponding abutment and means defining a generally cylindrical depression in the top of said body and intersecting each of said coin retaining cylinders and interrupting a portion of the walls thereof to allow a coin to be moved from said depression directly into the corresponding coin retaining cylinder.

2. A pocket size coin case for carrying a plurality of coins of each of a number of denominations and comprising a body portion, a plurality of adjacent coin retaining cylinders, one for each denomination, within said body adjacent the periphery thereof, a depression formed in the

top of said body and intersecting each of said cylinders to interrupt slightly more than half of the periphery of the upper portion of the walls thereof, a plurality of crescent shaped abutments, one for each cylinder, integrally formed with said body and overhanging the top of the corresponding cylinder, a plurality of slots, one corresponding to each cylinder, of a length at least as great as the diameter of the corresponding cylinder, and of a width slightly greater than the thickness of a coin of a denomination retained by said cylinder, each of said slots connecting the wall adjacent the top of the corresponding cylinder with the outside of said body, a plurality of flat spring arms, one for each cylinder, secured adjacent the lower end of the corresponding cylinder and extending into said cylinder to engage the lowermost coin present therein, said spring arms being constructed and disposed to retain the top coin present in the corresponding cylinder against the undersurface of the corresponding crescent shaped abutment and the end of each spring arm being proportioned and disposed to coincide with a chord connecting two portions on the undersurface of the corresponding abutment when the corresponding cylinder is empty.

3. A pocket size coin case for carrying a plurality of coins of each of a number of denominations and comprising a generally cylindrical body, a plurality of mutually adjacent coin retaining cylinders, one for each denomination, within said body and disposed around the periphery thereof, a generally cylindrical recess formed in the top of said body and intersecting each of said cylinders to interrupt approximately half of the periphery of the upper portion of the walls thereof, a plurality of slots, one adjacent each cylinder, of a length at least as great as the diameter of the corresponding cylinder and of a width slightly greater than the thickness of a coin of the denomination retained by said cylinder, each of said slots extending from the outside of said body and intersecting the corresponding cylinder adjacent the top thereof, a plurality of continuous abutments, one for each cylinder, supported by the top of said body above the top of the corresponding cylinder, projecting a relatively short distance inwardly past the walls of said cylinder, and terminating adjacent the intersection of the periphery of said recess and the walls of said cylinder, a plurality of intersecting flat spring arms, one for each cylinder, intersecting adjacent the lower end of the axis of said body, each of said arms extending into the corresponding cylinder to engage the lowermost coin present therein, a recess formed in the bottom of said body to receive the intersecting portions of said spring arms and interrupting the walls of each of said cylinders to provide an opening between said recess and said cylinder, said spring arms being constructed and disposed to engage the under surface of the corresponding continuous abutment when said cylinder is empty, and a removable bottom plate closing the bottom of said body and engaging the intersecting portion of said spring arms to retain said arms in position.

4. The combination claimed in claim 1, characterized in that a plurality of projections are carried by said body and disposed adjacent the periphery of said coin retaining cylinders, and extend upwardly from the bottom of said recess to a point slightly below the level of the bottom of the upper coin therein to engage the

periphery of the coin immediately below said uppermost coin and prevent it from sliding from said cylinder toward the center of said case.

6. A pocket size coin case for carrying a plurality of coins of each of a number of denominations and comprising a generally cylindrical body, a plurality of mutually adjacent coin retaining cylinders, one for each denomination, within said body and spaced inwardly a short distance from the periphery thereof, means defining a depression in the top of said body and intersecting each of said cylinders to interrupt approximately half of the periphery of the upper portions of the walls thereof, a plurality of crescent shaped abutments, one for each cylinder, integrally formed with said body, located to overhang approximately the outer half of the top of the corresponding cylinder, and terminating adjacent the intersection of the periphery of said depression with the walls of said cylinder, a plurality of slots, one adjacent the top of each cylinder, of a length at least as great as the diameter of the corresponding cylinder and of a width slightly greater than the thickness of a coin of the denomination retained by said cylinder, connecting the top of the cylinder with the outside of said body, the upper portion of the periphery of each slot being substantially coplanar with the undersurface of the corresponding abutment, a recess to accommodate a flat spring formed in the lower portion of said body and intersecting each of said coin retaining cylinders to interrupt the walls thereof adjacent the lower end of the cylinder, the periphery of said body being extended downwardly past the bottom of said cylinder, the extension so formed being internally threaded, a flat spring having a plurality of spring arms, one for each cylinder located with its central portion in said last-named recess and with one of said spring arms extending into each of said cylinders, said spring arms being shaped and disposed so that their outer ends coincide with a chord connecting two points on the undersurface of the corresponding crescent shaped abutment when said case is empty, and an externally threaded flat disk, having threads engageable with the threads formed on the extension of said body, closing the bottom of said case and retaining said spring in position.

6. A pocket size coin case for carrying a plurality of coins of each of a number of denominations and comprising a generally cylindrical body, a plurality of coin retaining cylinders, one for each denomination, within said body and disposed around the periphery thereof, abutment means carried by said body and overhanging the top of each of said cylinders, said abutment means having downwardly directed coin engaging surfaces substantially parallel to the tops of said cylinders and being constructed and disposed to permit the insertion and removal of a coin from the corresponding cylinder by sliding said coin along said coin engaging surfaces, means defining a recess in the bottom of said body and intersecting each of said cylinders adjacent the lower end thereof to form an opening in the walls of each cylinder, a flat spring comprising a plurality of flat spring arms, one for each cylinder, located with its central portion in said recess and with a spring arm extending into each of said cylinders, each of said spring arms being shaped and disposed so that its outer ends coincide with a line connecting two points on the coin engaging surface of said abutment means above the top of the corresponding cylinder when

the cylinder is empty, a removable flat disc closing the bottom of said case and retaining said spring in position, and means for retaining said disc to the bottom of said body.

7. A pocket size coin case for carrying a plurality of coins of each of a number of denominations and comprising a body, a plurality of coin retaining cylinders, one for each denomination, within said body and disposed around the periphery thereof, means defining a generally circular cavity in the top of said case, intersecting each of said cylinders at a point below the undersurface of the top coin present therein and interrupting approximately half of the periphery of the walls of the cylinder, thereby forming a rim extending around the top of said body and defining an area within which coins may be manipulated incidental to the placing of the coins in their respective cylinders, a plurality of projections, one adjacent each side of each cylinder, extending upwardly from the bottom of said recess to a point approximately opposite the undersurface of the top coin in the corresponding cylinder, abutment means overhanging the top of and projecting a small distance past the periphery of each of said cylinders for slidably engaging the top coin present therein to retain the coins in the cylinder, said abutment means and said body being constructed and disposed to permit a coin to be moved from said depression, across the top of the proper coin retaining cylinder, and past the periphery of said case, and resilient means held in compression by the bottom coin in each of said cylinders to press the top coin present in the cylinder against said abutment means.

8. A pocket size coin case for carrying a plurality of coins of each of a number of denominations and comprising a body, a plurality of mutually adjacent coin retaining cylinders, one for each denomination, within said body and disposed around the inside of the periphery thereof and spaced inwardly a short distance therefrom, means defining a depression in the top of said body and intersecting each of said cylinders to interrupt approximately half of the periphery of the upper portion of the walls thereof, thereby forming a rim extending around the top of said body, a plurality of crescent shaped abutments, one for each cylinder, formed in said rim and located to overhang approximately the outer half of the top of the corresponding cylinder, a plurality of slots, one adjacent the top of each cylinder, of a length at least as great as the diameter of the corresponding cylinder and of a width slightly greater than the thickness of a coin of the denomination retained by said cylinder, extending through the rim to provide for the passage of a coin from the top of the cylinder through said slot to the outside of said case, resilient means to retain the top coin present in each of said cylinders against said crescent shaped abutment, and a plurality of indicating knobs carried by the upper surface of said rim, said knobs being arranged with a distinctive number of knobs adjacent each of said cylinders, whereby the operator of the case may ascertain the denomination of the coins in each of the cylinders by the sense of touch.

9. A pocket size coin case for carrying a plurality of coins of each of a number of denominations and comprising a body, a plurality of coin retaining cylinders, one for each denomination, within said body and disposed around the periphery thereof, means for retaining the coins

in each of said cylinders, means for permitting the insertion and removal of coins into and from each cylinder, means defining a recess in the bottom of said body and intersecting the walls of each of said cylinders adjacent the lower end thereof to form openings connecting said recess with each of said cylinders, a flat spring comprising a plurality of flat spring arms, one for each cylinder, intersecting at the central portion of said spring, a hole formed in the central portion of said spring and located to coincide with the axis of said body when said spring is in position with its central portion in said recess and one arm extending through each of said openings into a corresponding cylinder, a detachable bottom for said case having threads formed thereon, means providing threads carried by said body and engageable with the threads formed in said bottom, a peg carried by said bottom and located in the center thereof to pass through said hole when said case is assembled, thereby retaining said spring in position.

10. A pocket size coin case for carrying a plurality of coins of each of a number of denominations and comprising a body, a plurality of coin retaining cylinders, one for each denomination, within said body, means defining a generally circular cavity intersecting each of said cylinders at a point below the under surface of the top coin present therein, thereby forming a rim extending around the top of said body and defining an

area within which coins may be manipulated incidental to the placing of the coins in their respective cylinders, means for retaining the coins in each of said cylinders, said cavity permitting the insertion of coins into the top of each cylinder, directly from the top central portion of said body, and means for permitting the removal of coins from the top of each of said cylinders by moving said coins directly past the outer margin of said body and resilient means for retaining the coins in each cylinder in a position adjacent the top thereof.

15. A pocket size coin case for carrying a plurality of coins of each of a number of denominations, comprising an integral body having a plurality of mutually adjacent coin retaining cylinders formed therein and a generally circular cavity intersecting each of said cylinders at a point below the under surface of the top coin present therein, thereby forming a rim extending around the top of said body and defining an area within which coins may be manipulated incidental to the placing of the coins in their respective cylinders, there being a coin ejecting 20 passageway extending through said body adjacent the open end of each cylinder, said body providing abutment means overhanging the top of each of said cylinders, and resilient means in each of said cylinders to press the top coin in 25 each cylinder against said abutment means.

RICHARDS L. LOESCH.
